United States Patent Office

Des. 222,563
Patented Nov. 2, 1971

222,563

BINOCULAR

Paul R. Maguire, Los Angeles, Calif., assignor to
David P. Bushnell, Altadena, Calif.

Filed Feb. 16, 1970, Ser. No. 21,442

Term of patent 14 years

Int. Cl. D16—08

U.S. Cl. D57—1

FIG. 1.

FIG. 3.

FIG. 2.

FIG. 4.

FIG. 5.

FIG. 1 is a front elevational view of the binocular, showing my new design,

FIG. 2 is a top plan view of the binocular,

FIG. 3 is a side elevational view of the binocular, both sides are identical,

FIG. 4 is a rear elevational view of the binocular, and

FIG. 5 is a bottom plan view of the binocular.

I claim:

The ornamental design for a binocular, as shown and described.
